UNITED STATES PATENT OFFICE.

JOSEPH S. O'BRIEN, OF WESTFIELD, MASSACHUSETTS.

DISPENSING TOILET-PAPER HOLDER.

Application filed June 10, 1922. Serial No. 567,479.

To all whom it may concern:

Be it known that I, JOSEPH S. O'BRIEN, a citizen of the United States of America, and a resident of Westfield, in the county 5 of Hampden and State of Massachusetts, have invented a new and useful Dispensing Toilet-Paper Holder, of which the following is a specification.

My invention relates to improvements in 10 devices for holding and supporting packages of flat toilet-paper, which devices are provided with means for delivering such toilet-paper a sheet at a time, and consists essentially of a suitable backing and supporting 15 means therefor and for a package of flat toilet-paper placed against or in front of said backing, and a feeding flap connected by flexible means with said backing, together with such other parts and members 20 or elements as may be necessary or desirable in order to render the device complete in every respect, all as hereinafter set forth.

The primary object of my invention is to produce a very simple and inexpensive device 25 for holding a package of flat toilet-paper, and dispensing the same, one sheet after another, by merely moving a feeding member up in front of said package and down in contact with the foremost sheet 30 therein.

Another object is to produce such a device or holder which is capable of receiving and handling any ordinary package of flat toilet-paper, and of utilizing the binder wire of 35 such package for the support of the latter, all without necessitating any change in the general form of either the package or wire.

The parts of this device and a package of 40 toilet-paper can be easily and quickly assembled, and after one package has been exhausted another can be placed in position in the holder without difficulty, fresh packages being supplied as often as may be necessary 45 until the holder is worn out.

Other objects and advantages will appear in the course of the following description.

I attain the objects and secure the advantages of my invention by the means illustrated in the accompanying drawings, in which—

Figure 1 is a front elevation of a dispensing toilet-paper holder which embodies a practical form of my invention, a package 55 of toilet-paper being in place in said holder; Fig. 2, a side elevation of said holder and

package, operative positions of the dispensing or feeding parts being represented by broken lines; Fig. 3, a reduced plan of the inside of the holder as it appears when opened out or laid flat, the metallic supporting member being omitted; Fig. 4, a similar view of a slightly modified form of construction, and, Fig. 5, a fragmentary detail in plan of a portion of a feeding flap which embodies still another modification, the inner surface of such flap appearing, and the detail being of substantially the same size as corresponding parts of the flap in the first two views.

Similar reference characters designate similar parts throughout the several views.

In Figs. 1 and 2 an ordinary package of flat toilet-paper is represented at 1, and an ordinary binder wire therefor at 2, such wire having a loop or eye 3 at one end as is customary. Ordinarily the end of the wire 2, which is opposite to the end thereof where the eye 3 is located, is bent over onto the contiguous side of the package, but for use in connection with my holder said first-named terminal must either be left unbent initially or bent into line with the other straight portion of said wire, depending on whether the package be placed in the holder at the factory, or be subsequently placed therein. If the package 1 be provided with pieces of cardboard over the back and front sides thereof, as is usually the case when flat toilet-paper is prepared and shipped without other holding means than the binder wires, the front piece must be removed and the back piece may be removed before the package is placed in the holder.

Referring to the first three views, it will be seen that the holder therein illustrated comprises a backing 4, a feeding flap 5 articulated to, or connected by means of a flexible connection 6, with the upper edge of said backing, said flap having a central, longitudinal opening 7 in the part thereof that is contiguous with the connection 6, and being provided with a block, feeding block, or feeder 8 located between the free end of said flap and said opening, and a supporting member or hanger 9. There is an opening 10, in the longitudinal center of the backing 4 near the top thereof, to permit of the passage therethrough of the front terminal portion of the hanger 9.

The backing 4 may be of any suitable size or shape, and said backing, together with

the flaps 5 and the flexible connection 6 may be made of a single sheet of cardboard, fiber-board, or similar material. In such event the flexibility of the connection 6 is increased by perforating or scoring the sheet of material transversely between the backing 4 and said connection, between the flap 5 and said connection, and one or more times intermediately of the joints formed by the two first-named scorings, these scorings being indicated by the numeral 21. In this manner provision is made for a degree of flexibility that enables the flap 5 to be moved up and down freely to the extent required.

15 The feeder 8 here consists of a wood block slotted, from one end nearly through to the other end, to receive that portion of the flap 5 which is below the opening 7 or between said opening and the free end of said flap. 20 The block 8 may be glued to the flap 5 if desired. The back or inner face of this block or feeder is made rough or provided with abrasive material in order to enable the same firmly to engage or be engaged 25 with a sheet of paper. It is necessary that a firm engagement be attained between the feeder 8 and the sheet of paper to be dispensed from the package 1, and any suitable means for this purpose, other than abrasive 30 material, may be employed or provided, although such means preferably should not perforate the paper.

The hanger 9 is bent upwardly at the rear end, and provided at the top of the upturned part with a loop or eye 11, and said hanger is bent downwardly at the front end, and provided at the bottom of the down-turned part with a loop or eye 12.

In assembling the parts, the forward terminal of the hanger 9 is inserted through the opening 10 in the backing 4 from behind, and passes through the eye 3 of the binder wire 2, and the forward terminal of said wire is inserted in the eye 12. Thus it is seen that the package 1 is suspended from the hanger 9 by means of the wire 2 and its eye 3, with the horizontal part of said hanger above said package, and the latter against the backing 4 and between said backing and the downwardly-turned terminal of said hanger. The holder with the package 2 is suspended from a hook or other suitable support by engaging the eye 11 with the same. When thus suspended the package hangs approximately vertically and the wire 2 and the horizontal portion of the hanger 9 are approximately parallel. If desired, the protruding portion of the wire 2 in front of the eye 12 may be bent to form an angle with said wire behind for the sake of further security.

The connection 6 extends over the hanger 9 in front of the up-turned terminal thereof, and over the top of the package 1, resting on the front-terminal portion of said hanger;

and the flaps 5 hangs down from said connection with the inner, abrasive face of the feeder 8 against the front sheet of paper in said package, and some distance below the eye 12 which supports the wire 2 at the forward terminal, such distance being sufficient for the feeding operation which will presently be explained—see full lines in Fig. 2.

The portion of the feeder block 8, which is in front of that portion of the flap 5 to which said block is attached, is thicker than the portion of said block that is behind said portion of said flap, such front portion of the block projecting far enough to afford a good grip for the thumb and finger in moving the block up and down.

In practice, the feeder block 8 is grasped and moved upwardly toward the eye 12, carrying with it the flap 5 and raising the connection 6, then said block is forced again the front sheet of paper in the package 1 and while held firmly against the same moved downwardly, with the result that such sheet is carried with the block, torn loose from the binder wire 2, and caused to project below the bottom of said package. The broken lines in Fig. 2 show the feeder part way down, with the flap 5 and connection 6 relatively disposed, and the front sheet projecting, as indicated by the broken lines at 13, below the bottom of the package. When the feeder has been moved down until the forward portion of the connection 6 comes to rest against the hanger 9, or possibly in some cases against the upper, front edge of the package 1, said feeder is released, the protruding portion of the foremost sheet is grasped between the thumb and finger, and said sheet is drawn from between the remaining sheets and the feeder.

The initial downward movement of the feeder causes the front sheet to be torn loose from the wire 2. A second sheet is obtained in the same manner as that just described, and so on until the package is exhausted. As the package decreases in size, the hanger 9 in front of the eye 3 and the wire 2 in front of said eye are received in the slot 7, so that they do not interfere with the successful operation of the feeder even when in the act of dispensing the last or rearmost sheet.

After the package 1 has been exhausted, the flap 5 and the connection 6 are swung upwardly, the wire 2 is removed from the hanger 9, a new package is placed in position and suspended from said hanger, and said flap and connection are returned to place, with the feeder 8 in front of said last-named package in readiness for partially detaching the sheets one at a time therefrom, as was done from the first package.

In the modification shown in Fig. 4, a feeder is made by providing an extension

14 at the free end of the feeding flap 5, and two lateral extensions 15 from the first, folding the extensions 15 under and over each other onto the extension 14, on score lines 16—16, and gluing or otherwise securing these parts together, and then folding the extension 14 with the extensions 15 glued thereto on score lines 17 onto said flap, into the position indicated by broken lines at 18, and gluing or otherwise securing the folded parts to said flap. This feeder is completed by applying abrasive material to the exposed face of the aforesaid folded parts, which face is the backside of the extension 14 as it is positioned in the drawing. The operation of this feeder and that of the associated parts are substantially the same as in the first example, except that it is necessary, in order to grasp the Fig. 4 feeder, to apply the thumb and finger to the free end of the flap and the adjacent edge of the opening 7.

The feeder illustrated in Fig. 5 consists merely of the free terminal portion 19 of the feeding flap 5, which portion is supplied on the inside with abrasive material. A tab 20 is struck out of the part 19 to serve as a handle with which to operate the feeder.

In each example the feeder, when in operative position, is located with its longitudinal, transverse center in the same vertical plane with the binder wire 2 and the hanger 9, so that a direct pull, in line with the supporting members for the package 1 at the top, is exerted on the foremost sheet of paper in said package, when said feeder is forcibly engaged with such sheet and moved downwardly. Thus provision is made for freeing the paper from the wire 2 in the most direct manner and to the best advantage.

More or less modification may be made in the device, in addition to the specific changes of which particular mention has been made, without departing from the spirit of my invention or exceeding the scope of what is claimed.

What I claim as my invention, and desire to secure by Letters Patent, is—

50 1. A dispensing toilet-paper holder comprising a perforated backing, a perforated flap having a feeding part, a foldable connection between said backing and said flap, the arrangement of parts being such that said flap can be moved up and down and swung forward and back, and a supporting member receivable in the perforation in said backing and in the eye of the binder wire of a package of toilet-paper, and adapted to support said wire at the terminal opposite to said eye, said supporting member and said wire both being receivable in the perforation in said flap, whereby said flap is permitted to be operated and by 65 gravity normally to contact with the toilet-

paper regardless of the thickness of the package.

2. A dispensing toilet-paper holder comprising a one-piece element forming a back support, a feeding flap, and a foldable connection between the two for a package of paper and the sheets therein, and means to support said element and package. 70

3. A dispensing toilet-paper holder comprising a single-piece element forming a back support and a feeding flap for a package of paper and the sheets therein, such element being transversely scored to provide a flexible connection for said flap, and means to support said element and said package. 75

4. A dispensing toilet-paper holder comprising a perforated backing, a perforated feeding flap articulated to said backing, an abraded feeder block attached to said flap between the free end thereof and the adjacent edge of the perforation therein, and a hanger receivable in the perforation in said backing and in the eye of the binder wire of a package of toilet-paper, and adapted to support said wire at the terminal opposite to said edge, said hanger and said wire both being receivable in said perforation in the flap. 80

5. In a dispensing toilet-paper holder, supporting means, a flap having a feeding part for individual sheets of paper, and a flexible connection between said means and said flap, said connection being constructed to enable the feeding part of said flap normally to contact by gravity with the paper regardless of the thickness of the supply thereof, and to permit said flap to move upward and downward and forward and backward. 95

6. In a dispensing toilet-paper holder, supporting means, a flap provided with a feeder for individual sheets of paper, and a flexible connection between said means and said flap, said connection being constructed to enable said feeder normally to contact by gravity with the paper regardless of the thickness of the supply thereof, and to permit said flap to be moved upward and downward and forward and backward. 105

7. In a dispensing toilet-paper holder, supporting means, a flap provided with a feeder for individual sheets of paper, and further provided with means to be grasped for the purpose of operating said flap, and a flexible connection between said means and said flap, said connection being constructed to enable said feeder normally to contact by gravity with the paper regardless of the thickness of the supply thereof, and to permit said flap to be moved upward and downward and forward and backward. 110
